By E. E. Trooman, his Attorney.

UNITED STATES PATENT OFFICE.

GEORGE F. WILLIS, OF YERINGTON, NEVADA.

COIN-TRAY.

1,095,256.

Specification of Letters Patent.

Patented May 5, 1914.

Application filed October 22, 1912. Serial No. 727,249.

To all whom it may concern:

Be it known that I, GEORGE F. WILLIS, a citizen of the United States, residing at Yer-
ington, in the county of Lyon and State of
5 Nevada, have invented certain new and use-
ful Improvements in Coin-Trays, of which
the following is a specification, reference
being had therein to the accompanying
drawing.

10 This invention relates to coin trays and
has special reference to a novel form of coin
tray so provided with indicating devices that
the number of coins in the tray and the
number of coins desired to be removed may
15 be indicated to the eye without the necessity
of counting the same.

The principal object of the invention is to
improve and simplify the general construc-
tion of devices of this character.

20 With the above and other objects in view,
this invention consists in general of certain
novel constructions, combinations and ar-
rangements of parts, as will be hereinafter
fully described, illustrated in the accom-
25 panying drawings, and specifically claimed.

In the accompanying drawings, like char-
acters of reference indicate like parts in the
several views, and Figure 1 is a plan view
30 of the coin tray constructed in accordance
with this invention. Fig. 2 is a bottom view
thereof. Fig. 3 is a section on line 3—3 of
Fig. 2. Fig. 4 is a side elevation. Fig. 5 is
a view showing a slight modification in order
35 to better disclose the desired scale arrange-
ment, the divisional members being shown at
the corners in place of the middle of the
sides of the tray as in Fig. 4.

In the construction of this tray there is
provided a block 10 of substantially rec-
40 tangular form in the original blank as indi-
cated by the dotted lines in Fig. 1, it being
understood that these dotted lines do not
form part of the completed invention. This
blank is bored out or otherwise formed with
45 cylindrical pockets 11 of such size as to ac-
commodate the coins it is desired to hold in
the tray. These coins may either be of uni-
form value in all of the pockets, or may vary
in value. There is also provided a centrally
50 disposed pocket 12. The corner pockets 11

are provided with bottoms 13 of segmental
form, the balance of the corner being cut
away as clearly shown in Fig. 1. The cen-
tral pocket 12 is provided with an annular
flange 14 forming a bottom and arranged to 55
leave a finger hole 15. A side slot 16 is cut
between the center and one corner pocket.
Arranged on the flattened portions of the
sides, either at the corner or in the middle
of the rectangular block are gage lines 17 60
having gage numbers 18 adjacent the same.
By referring to Fig. 5 it will be seen that
the scale on opposite sides of a pocket is re-
versed.

When using this device the coins are 65
dropped in the respective pockets and the
number of coins in a pocket is indicated by
the scale which begins at the bottom of the
pocket. Now, if it be desired to remove a
given number of coins, it is simply neces- 70
sary to insert the thumb nail beneath the
proper coin, this being indicated on the scale
beginning with the zero at the top and run-
ning downward. The separate coins may
then be lifted out. By referring to the 75
drawing it will be seen that one of the corner
pockets 11 communicates with the central
pocket 12 by means of the sight slot 16.
Since the outer portion of the tray is pro-
vided with a gage to determine the number 80
of coins within the pocket, or the exact
amount contained in the pocket 12 may be
told by referring first to the gage and then
glancing through the sight slot 16 and view-
ing the stack contained in the pocket 12. 85
When the amount in the pocket 12 has been
determined a person may insert his finger
through the hole 15 and force the coins up-
wardly until a desired amount has passed
from the pocket 12. 90

Having thus described the invention, what
is claimed as new, is:—

A coin tray comprising a squared body
having grooved corners, said body provided
with vertically-extending sockets of differ- 95
ent sizes adapted to receive different sized
coins, said body provided with a gage at its
outer portion adjacent each coin pocket, said
body provided with a centrally-located coin
pocket and having a transversely-extending 100

groove extending from said central coin pocket to one of said corner coin pockets whereby the exact amount contained in the central pocket may be ascertained by viewing the coin through said groove, and said body provided with a finger-hold in the lower portion of said central pocket whereby a person may insert a finger therethrough

and force the desired number of coins from said central pocket.

In testimony whereof I hereunto affix my signature in presence of two witnesses.

GEORGE F. WILLIS.
